(57) **CLAIM**

The ornamental design for a chair, as shown and described.

DESCRIPTION

FIG. 1 is a perspective view of a first embodiment of the ornamental design for a chair according to the invention; FIG. 2 is a left side elevational view of the chair of FIG. 1, the right side view being a mirror image thereof; FIG. 3 is a front elevational view of the chair of FIG. 1; FIG. 4 is a rear elevational view of the chair of FIG. 1; FIG. 5 is a top plan view of the chair of FIG. 1; FIG. 6 is a bottom plan view of the chair of FIG. 1; FIG. 7 is a perspective view of a second embodiment of the ornamental design for a chair according to the invention; FIG. 8 is a left side elevational view of the chair of FIG. 7, the right side view being a mirror image thereof; FIG. 9 is a front elevational view of the chair of FIG. 7; FIG. 10 is a rear elevational view of the chair of FIG. 7; FIG. 11 is a top plan view of the chair of FIG. 7; and, FIG. 12 is a bottom plan view of the chair of FIG. 7. Portions of drawings shown in phantom outline are for illustrative purposes only and form no part of the claimed invention.

UNITED STATES PATENT AND TRADEMARK OFFICE
CERTIFICATE OF CORRECTION

PATENT NO. : D522,766 S
APPLICATION NO. : 29/212698
DATED : June 13, 2006
INVENTOR(S) : Robert L. Russell et al.

Page 1 of 12

It is certified that error appears in the above-identified patent and that said Letters Patent is hereby corrected as shown below:

Delete the title page and substitute therefor the attached title page consisting of the corrected
illustrative figures 1 and 7.

Delete Drawing Sheets 1-10 and substitute therefore the attached Drawing Sheets 1-10 consisting of
FIGS. 1-12.

Signed and Sealed this
Twenty-third Day of July, 2013

Teresa Stanek Rea
Acting Director of the United States Patent and Trademark Office
